PERFUME CONTAINER OR SIMILAR ARTICLE

Giulio Linetti, Venice, Italy

Application April 30, 1954, Serial No. 30,267

Term of patent 14 years

(Cl. D86—10)

FIG. 1

FIG. 2

FIG. 4

Fig. 1 is a front elevation of a perfume container or similar article showing my new design.

Fig. 2 is a plan view of the same looking down.

Fig. 3 is an end elevation of the same looking from left to right.

Fig. 4 is an end elevation of the same looking from right to left.

What I claim is:

The ornamental design for a perfume container or similar article, as shown.
